UNITED STATES PATENT OFFICE.

RUDOLPH T. REINSPERG, OF LOUISVILLE, KENTUCKY.

COAT SACKER.

Application filed November 5, 1925. Serial No. 67,187.

This invention relates to improvements in coat sackers, and has for one of its principal objects the provision of means whereby coats and suits, after being cleaned or the like, 5 may be conveniently and readily placed in sacks, bags or other suitable coverings for purposes of delivery or storage.

One of the principal objects of this invention is to provide, in a coat sacker, new and 10 useful means for supporting coats or suits upon hangers or the like, and in position for ready insertion into bags or other coverings, and with a minimum expenditure of time and labor.

Still another important object of this invention is to provide, in a coat sacker, means for elevating and depressing a support for a coat hanger or the like in order to allow of a ready and economical application of a suitable container to a coat, suit, or other similar article.

Other and further important objects of this invention will be apparent from the disclosures in the accompanying drawings and 25 following specification.

The invention, in a preferred form, is illustrated in the drawings and hereinafter more fully described.

In the drawings:

Figure 1 is a front elevation of the improved coat sacker of this invention, shown in its elevated position.

Figure 2 is a similar view, parts being broken away and in section, showing the device in its lowered position and illustrating the operating parts.

Figure 3 is a side view, partly in section, showing further details of construction.

As shown in the drawings:

The reference numeral 10 indicates generally the base of the improved coat sacker of this invention, adapted to be suitably positioned upon a floor and solidly maintained thereon by means of bolts 12 or the like.

Mounted on the base 10 is an upstanding element 14 within which is slidably and telescopically mounted a corresponding element 16 which has, in turn, telescopically mounted therein an additional extension 18. At the 50 top of the member 18 is affixed a hook 20 for the purpose of removably supporting the coat hanger or similar member.

An operating lever 22 is pivotally mounted upon an upstanding lug 24 on the base 10, 55 and has co-operating therewith a spring operated latch 26 adapted to automatically re-

tain the pedal or lever 22 in lowered position. The short end of the lever 22 co-operates, in turn, with the short end of a similar lever 28 pivotally mounted at 30, as shown in Figure 3, and with its longer end extending into a housing 32 mounted on the base 10.

The free end of the lever 28 has attached thereto one end of a chain or cable 34 which is wrapped around a small pulley 36, the pulley 36 being affixed to or integral with a larger pulley 38 adapted to rotate therewith.

Upon this larger pulley 38 is mounted a chain or cable 40, one end of which is wrapped around a corresponding smaller pulley 42, which, in turn, is integral with or affixed to a larger pulley 44.

Affixed to the wheel 44 and running over a pulley 46 is a chain or cable 48, having its free end attached to the lower end of the telescopic element 16.

A pulley 50 similar to the pulley 46 is mounted at the top of the element 16, and in the interior thereof and over this pulley passes a cable or cord 52, one end of which is affixed to the base 10 at 54, and the other end of which is affixed to the bottom of the telescopic member 18.

Upon depression of the pedal or lever 22 the short end of this lever raises the short end of the lever 28, depressing the other end of this lever and causing the small pulley 36 to rotate under the tension of the cable or chain 34. This, in turn, rotates the large wheel or pulley 38, winding the cable 40 thereupon, and rotating the pulleys 42 and 44. This rotation retracts the cable 48 over the pulley 40, elevating the member 16.

The elevation of the member 16 carries with it the pulley 50, which, in turn, causes the end of the cable 52 affixed to the member 18, to rise, thereby causing a corresponding elevation of the member 18 at a rate and through a distance equal to twice the corresponding rate and distance of the member 16.

It will be seen that herein is provided a collapsible telescopic coat sacking stand which can be conveniently raised to a height of approximately 6 ft. From an original stand of approximately 2 ft., thereby allowing of a very convenient sacking of a coat, suit, or other object positioned upon a hanger or the like on the hook 20. As soon as the coat is sacked, which sack can be procured from a rack in the ceiling or over the head of the operator and slip down over

the dress or coat, an opening being provided in the bottom of the sack for this purpose, the latch 26 is released, thereby allowing the elements 16 and 18 to drop by gravity into 5 the member 14, leaving the completely sacked or covered coat or other object in the operator's hands ready for delivery or storage.

I am aware that many changes may be 10 made and numerous details of construction varied throughout a wide range without departing from the principles of this invention, and I therefore do not purpose limiting the patent granted hereon otherwise than 15 as necessitated by the prior art.

I claim as my invention:

1. In a coat and dress sacker, the combination of a base, a plurality of supports telescopically mounted on said base for vertical movement, and means for elevating the supports, said means comprising a foot-operated lever pivotally mounted on the base, a lever positioned at right angles thereto also pivotally mounted with respect to the base, 20 the two shorter ends of said levers contacting for operative relation, a cable attached to the longer end of the last named lever, a relatively small drum on which said cable is mounted, said drum being mounted to rotate with a larger drum on the same shaft, another cable on the larger drum, the free end of said last named cable being wound about a comparatively small drum on another shaft, a larger drum mounted to 25 rotate with said last named small drum and on the same shaft therewith, a cable on said 30 35

last named larger drum; the free end of said cable passing over a pulley and connected to the lower end of one of said telescopic members.

2. In a coat and dress sacker, the combination of a base, a plurality of supports telescopically mounted on said base for vertical movement, and means for elevating the supports, said means comprising a foot-operated lever pivotally mounted on the base, a lever positioned at right angles thereto also pivotally mounted with respect to the base, the two shorter ends of said levers contacting for operative relation, a cable attached to the longer end of the last named lever, 40 a relatively small drum on which said cable is mounted, said drum being mounted to rotate with a larger drum on the same shaft, another cable on the larger drum, the free end of said last named cable being wound about a comparatively small drum on another shaft, a larger drum mounted to rotate with said last cable on said last named larger drum, the free end of said cable passing over a pulley and connected to the lower end of one of said telescopic members, and a further cable mounted in said telescopic member having one end attached to the base 45 and passing over a pulley in said telescopic member, and with its other end attached to a further telescopic member movably mounted with respect to the said first named telescopic member.

In testimony whereof I affix my signature,

RUDOLPH T. REINSPERG.
